SELF-CONTAINED PORTABLE TOILET

Elias D. Quintana, La Mirada, Calif., assignor to Mission-West Manufacturing Company, Los Angeles, Calif.

Filed June 1, 1970, Ser. No. 23,247

Term of patent 14 years

Int. Cl. D23—02

U.S. Cl. D23—48

FIG. 1 is a perspective view of a self-contained portable toilet showing my new design;

FIG. 2 is a right side elevational view of the same;

FIG. 3 is a top plan view thereof;

FIG. 4 is a front elevational view thereof; and

FIG. 5 is a rear elevational view thereof.

I claim:

The ornamental design for a self-contained portable toilet, as shown.
